UNITED STATES PATENT OFFICE.

JOSEPH C. WALKER, OF HELENA, MONTANA TERRITORY.

WAGON-BRAKE.

SPECIFICATION forming part of Letters Patent No. 245,329, dated August 9, 1881.

Application filed June 11, 1881. (No model.)

To all whom it may concern:

Be it known that I, JOSEPH CULTON WALKER, a citizen of the United States of America, residing at Helena, in the county of Lewis and Clarke and Territory of Montana, have invented certain new and useful Improvements in Wagon-Brakes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to an improvement in self-acting wagon-brakes; and it consists in the peculiar construction and arrangement of parts whereby the gravity of the wagon applies the brakes to the wheels in descending an incline.

It also consists in the use of a spring, whereby the action of releasing the brakes from the wheels is assisted, and whereby the draft is rendered easier upon the horses by removing, in part, the jar upon their shoulders; and it further consists in a device whereby the wagon may be backed without applying the brakes to the wheels, all of which will be more fully set forth hereinafter.

The accompanying drawings illustrate my invention.

Figure 1 is a side elevation. Fig. 2 is a top plan view. Fig. 3 is a perspective view of the combined spring and hanger. Fig. 4 is an enlarged view of the locking device.

A represents the front portion of the running-gear of a wagon. B is the tongue. The rear end of the tongue is provided with a slot, b, for the admission of the lever c, which is fulcrumed at d in the hanger e which depends from the lower side of the tongue. This hanger e is made of steel or other suitable material, being broad and thin, and being bent into the shape shown in Figs. 1 and 3, having a slot, e', made in it to admit of the passage of the lever c.

When the power is applied in applying the brakes to the wheels it is accomplished, in part, against the tension of the spring-hanger e, the forward portion, e², becoming partially straightened, and the rear portion, e³, becoming more curved, as will be readily understood. The

instant the strain is taken off by arriving at the foot of the hill the spring, in becoming restored to its normal shape, throws the brakes from the wheels a slight distance, thus assisting the team in releasing the brakes. This spring also renders the draft easier upon the horses by relieving the jar and strain of the draft upon their shoulders.

The lower end of the lever c is slightly curved, and fits into the bifurcated end of the brake-rod C, the brake-rod having two friction-rollers, one before and one behind the end of the lever c, as shown. The brake-rod C is in two pieces, f and g, as shown, their ends being converted into right and left hand screws, respectively, and connected by the link h, the ends of the link being tapped to fit the screw-ends of the parts f and g. By this arrangement the brake-rod may be lengthened or shortened, as desired.

Bearing on the top of the tongue B is the connecting-rod i, one end of which is pivoted to the lever c, as at k, the other end securing the evener or double-tree, to which the draft is applied. This connecting-rod is provided with the friction-rollers l, as shown.

To the extreme upper end of the lever c is pivoted a second connecting-rod, m, the other end of which is pivoted to the rod n, which extends along the tongue B, its outer end receiving the pull-back chains of the horses' harness.

It will be observed that the lever c is fulcrumed to the spring-hanger at a point about one-third of its length from the bottom, thus securing great power in applying the brakes.

When backing the wagon it is necessary to make some provision for keeping the lever from moving as the team tugs against the front end of the rod n, as the movement of the rod would apply the brakes to the wheels, thus giving the horses an additional and unnecessary resistance to overcome. This I accomplish by means of the device shown in Fig. 4.

Through the rear end of the rod n is made a hole, o, which registers with another hole, p, made in the tongue, when the rod is at the forward limit of its movement. A little to the rear of the hole o, upon the rod n, is fixed a standard, q, in which is pivoted a bent arm, r, having its lower end, s, much larger and heavier than the horizontal arm t, as shown.

To the outer end of the arm *t* is pivoted a coupling-pin, *r*, which hangs down with its lower end in the hole *o*, stopping short of entering the hole *p* in the tongue, the weighted 5 end of the bent arm counterbalancing the pin *v* and arm *t*.

To the weighted end of the arm is fastened one end of a cord, *w*, the other end passing up to the driver. Before backing the team the 10 driver pulls the cord, which causes the pin *v* to enter the hole *p* in the tongue, thus preventing the rod *n* from moving back and applying the brakes to the wheels. The strain upon the 15 pin while the team is backing will be more than sufficient to keep it in the hole *p*, while the counter-weight will withdraw it from the hole in the tongue when the team is started forward.

Having thus described my invention, I 20 claim—

1. The combination of the tongue *B*, rod *n*,

connecting rods *i* and *m*, (the rod *m* being connected to rod *n* and lever *c*, the rod *i* being connected to the double-tree and lever *c*), lever *c*, hanger *e*, brake-rod *C*, and brake-bar carrying the brakes, substantially as shown 25 and described.

2. The rod *n*, provided with the standard *g*, and the bent arm or lever *r*, having one end heavier than the other, and connected with the tongue *B*, having the hole *p*, whereby the 30 rod *n* may be rigidly secured to the tongue *B* in backing, substantially as and for the purposes shown and described.

In testimony whereof I affix my signature in presence of two witnesses.

JOSEPH CULTON WALKER.
